US00D921734S

(12) **United States Design Patent** (10) Patent No.: **US D921,734 S**
(45) Date of Patent: ** Jun. 8, 2021

(54) **WEARABLE INDUSTRIAL ROBOTIC EXOSKELETON**

(71) Applicants: **Hyundai Motor Company**, Seoul (KR); **Kia Motors Corporation**, Seoul (KR)

(72) Inventors: **Kyu Jung Kim**, Seoul (KR); **Hyun Seop Lim**, Anyang-si (KR); **Ki Hyeon Bae**, Yongin-si (KR); **Ju Young Yoon**, Suwon-si (KR); **Dong Jin Hyun**, Suwon-si (KR); **Sang In Park**, Suwon-si (KR)

(73) Assignees: **Hyundai Motor Company**, Seoul (KR); **Kia Motors Corporation**, Seoul (KR)

(**) Term: **15 Years**

(21) Appl. No.: **35/509,217**

(22) Filed: **Mar. 7, 2019**

(80) **Hague Agreement Data**

Int. Filing Date: **Mar. 7, 2019**

Int. Reg. No.: **DM/207361**

Int. Reg. Date: **Mar. 7, 2019**

Int. Reg. Pub. Date: **May 1, 2020**

(51) **LOC (13) Cl.** **15-99**

(52) **U.S. Cl.**

USPC **D15/199**

CPC **A61H 3/00** (2013.01)

(58) **Field of Classification Search**

USPC D15/199; D21/369, 578-583, 621, 622; D24/190
CPC A61H 3/00; A61H 1/024; A61H 1/0244; A61H 2201/5097; A61H 2201/5061; A61H 2201/5071; A61H 2201/1623; A61H 2201/50; A61H 2201/5069; A61H 2201/165; A61H 2201/1207; A61H 2201/0165; A43B 3/0005

(57) **CLAIM**

The ornamental design for a wearable industrial robotic exoskeleton, as shown and described.

DESCRIPTION

1. Wearable industrial robotic exoskeleton

1.1 : Perspective

1.2 : Front

1.3 : Back

1.4 : Left

1.5 : Right

1.6 : Top

1.7 : Bottom

1.8 : Rear Perspective

1 Claim, 8 Drawing Sheets
